UNITED STATES PATENT OFFICE.

JOHN HERNACKI, OF ALEXANDRIA, LOUISIANA.

SHADE-ROLLER SUPPORT.

1,352,264.

Application filed January 7, 1919. Serial No. 270,045.

Patented Sept. 7, 1920.

To all whom it may concern:

Be it known that I, JOHN HERNACKI, a citizen of the United States of America, residing at Alexandria, in the parish of Rapides and State of Louisiana, have invented new and useful Improvements in Shade-Roller Supports, of which the following is a specification.

The purpose of the invention is to provide a new and novel form of shade roller support for attachment to the vertical stiles of a window frame. The support is so designed that it effects a gripping operation on top of the transverse architrave of the window frame and on both sides of the vertical architrave or stile of the frame and in the event that the frame at the top is of irregular contour on the face, provision is made for setting the support so that it will be held in a perpendicular position.

To the exact construction in which it is shown and described, the invention is not to be restricted. The right is reserved to make such changes or alterations as the actual reduction to practice may suggest, in so far as such changes or alterations are compatible in spirit with the annexed claim.

In the accompanying drawings:

Figure 1 is a front elevational view of one of the upper corners of a window frame showing the invention attached thereto.

Fig. 2 is a section on the line 2—2 of Fig. 1.

Fig. 3 is a section on the line 3—3 of Fig. 1.

Fig. 4 is a view partly in section and partly in elevation showing the device attached on the facing of a window frame when the latter is not flat.

Fig. 5 is a perspective view of the shade roller bracket employed in conjunction with the invention.

As shown, the invention is attached to a window frame, portions of the vertical stile 1 and transverse piece 2 of which are shown.

The invention comprises a body member 3 made preferably of flat steel and which in elevation has the shape substantially of a cross, being provided with lateral projections 4 in which and across the body member there is formed a slot 5. That portion of the body member above the lateral projections 4 terminates in a jaw element 6 provided with teeth 7 designed to engage in the top

edge of the transverse piece 2 or held between the said piece and the plaster forming the wall back of the frame.

A curtain pole support 8 is riveted or otherwise suitably attached to the body member 3 on that part between the lateral projections 4 and the jaw element 6.

Below the lateral projections 4, the body portion 3 is provided with a hole through which there is passed a bolt 9, the latter threadingly engaging the said hole.

A transverse member 10 is provided for attachment to the body member and this transverse member is formed with a longitudinal slot 11 through which the bolt 9 loosely passes. The transverse member 10 is further formed with a jaw element 12 having prongs 13 designed to engage the outside edge of the vertical stile 2 or to engage between the same and the plaster.

Further than the transverse member 10 there is provided a second transverse member 14 formed with a plurality of interconnecting holes 15 and further formed with a jaw element 16 carrying at its end a cushion 17 of rubber, felt or some other suitable material. The element or member 14 is attached to the bolt 9 by passing the latter through any one of the holes 15, after which the attachment of the wing nut 18 serves to secure the body member and the two transverse members together, the first gripping the window frame on the upper edge and the two latter gripping the vertical stile on the outer and inner edges. The holes 15 are provided so that the body member may be promptly positioned the first and the transverse member 14 thereafter positioned so that its cushion will lie against the inside edge of the vertical stile 1. It is obvious that were a plurality of holes 15 not provided, the body member could not be positioned centrally relative to the vertical stile of a window frame were the same of different width from that for which the device was originally designed. But the provision of the series of holes 15 enables the initial proper setting of the body member and thereafter the positioning of the transverse member 14 so that its cushion 17 will engage the inside edge of the vertical stile when the body member is centrally positioned with reference to said stile.

95

100

105

The transverse member 10, is obviously for the purpose of effecting a clamping operation in coöperation with the transverse member 14 after the latter and the body member have been positioned, as aforesaid.

Attachable to that portion of the body member wherein the lateral projections 4 are formed there is a shade roller supporting bracket 18 which is formed with a right angularly disposed base 19 inturned from which there is a lip 20, the latter loosely engaging in the slot 5. Centrally disposed in this base portion, there is a hole through which there is passed the bolt 21, the latter 10 passing also through the slot 5 and thus providing for the attachment of the shade roller bracket to the body member 3 so that it may be adjusted laterally with reference to the window frame on which the device is used.

20 In Fig. 4 there is shown a portion of a window frame in which the front face is irregular. The improved bracket is adapted for attachment to this character of window frame, the only modification necessary 25 being the replacement of the bolt 9 with a much longer bolt 22. Since either the bolt 9 or bolt 22 threadingly engages the hole in the body portion through which it passes, it is obvious that this bolt 22 may be 30 adjusted to have its head bearing against the facing of the window frame to hold the body away therefrom so as to maintain it substantially vertical. The bolt having once been set to accomplish this result, the 35 two transverse members 10 and 14 are at-

tached in the same way as they are to the bolt 9.

From the foregoing description, and the accompanying drawings it is believed that a clear enough understanding of the invention 4 is to be had to render further description unnecessary.

The invention having been described, what is claimed as new and useful is:—

A device of the kind described, comprising 41 a body member designed for vertical positioning on a window frame, a shade roller bracket adjustable on said body member, the said body member being formed with a jaw terminal designed to over hang 46 the upper edge of the window frame, a transverse member formed with the jaw terminal designed to engage the inner edge of the vertical stile of the window frame, the said transverse member being formed with 51 a plurality of interconnecting holes, a second transverse element formed with a jaw terminal for engagement with the outer edge of the vertical stile of the frame, the last said transverse member being formed 56 with a longitudinal slot, a bolt engaged with the body member and passing through any one of the interconnecting holes and through the said slot, and a wing nut attached to the bolt and serving to secure 61 the transverse members and the body portion together.

In testimony whereof I affix my signature.

JOHN HERNACKI.
